(57) **CLAIM**

The ornamental design for a propeller blade, as shown and described.

DESCRIPTION

FIG. 1 is a top-front-left perspective view of a propeller blade showing my new design;

FIG. 2 is a top-front-right perspective view thereof;

FIG. 3 is a top-rear-left perspective view thereof;

FIG. 4 is a top-rear-right perspective view thereof;

FIG. 5 is a bottom-front-left perspective view thereof;

FIG. 6 is a bottom-front-right perspective view thereof;

FIG. 7 is a bottom-rear-left perspective view thereof;

FIG. 8 is a bottom-rear-right perspective view thereof;

FIG. 9 is a front elevated view thereof;

FIG. 10 is a rear elevated view thereof;

FIG. 11 is a top plan view thereof;

FIG. 12 is a bottom plan view thereof;

FIG. 13 is a right elevated view thereof;

FIG. 14 is a left elevated view thereof;

FIG. 15 is an enlarged vertical cross-sectional view thereof taken in the direction of line 15-15 in FIG. 11;

FIG. 16 is an enlarged vertical cross-sectional view thereof taken in the direction of line 16-16 in FIG. 11;

FIG. 17 is an enlarged vertical cross-sectional view thereof taken in the direction of line 17-17 in FIG. 11;

FIG. 18 is an enlarged vertical cross-sectional view thereof taken in the direction of line 18-18 in FIG. 11;

FIG. 19 is an enlarged vertical cross-sectional view thereof taken in the direction of line 19-19 in FIG. 11;

FIG. 20 is an enlarged vertical cross-sectional view thereof taken in the direction of line 20-20 in FIG. 11;

FIG. 21 is an enlarged vertical cross-sectional view thereof taken in the direction of line 21-21 in FIG. 11;

FIG. 22 is an enlarged vertical cross-sectional view thereof taken in the direction of line 22-22 in FIG. 11;

FIG. 23 is an enlarged vertical cross-sectional view thereof taken in the direction of line 23-23 in FIG. 11;

FIG. 24 is an enlarged vertical cross-sectional view thereof taken in the direction of line 24-24 in FIG. 11;

(Continued)

FIG. 25 is an enlarged vertical cross-sectional view thereof taken in the direction of line 25-25 in FIG. 11; FIG. 26 is a top-front-left perspective view thereof, showing the propeller blade as part of a pump propeller; and, FIG. 27 is a bottom-front-left perspective view thereof. The broken lines showing a blade end in FIGS. 1-13, and the broken lines showing a propeller hub and propeller blades in FIGS. 26 and 27 are included for the purpose of showing environmental structure and form no part of the claimed design.

1 Claim, 27 Drawing Sheets
